UNITED STATES PATENT OFFICE.

HARRY BAINTON, OF NEW YORK, N. Y.

PNEUMATIC VALVE-ACTION.

No. 890,488.

Specification of Letters Patent.

Patented June 9, 1908.

Application filed November 9, 1907. Serial No. 401,411.

To all whom it may concern:

Be it known that I, HARRY BAINTON, a citizen of the United States, residing in New York, in the borough of the Bronx, county 5 and State of New York, have invented certain new and useful Improvements in Pneumatic Valve-Actions, of which the following is a specification.

This invention relates to an improved pneumatic valve-action for player-pianos, which 10 valve-action is simple and effective in construction, and responsive to the air which is drawn in through the perforations of the music-sheet and the channels of the tracker, 15 and the parts of which are conveniently and individually accessible for cleaning and repairing; and for this purpose the invention consists in certain novel features of construction which will be fully described hereinafter 20 and finally pointed out in the claim.

In the accompanying drawings, Figure 1 represents a top-view of my improved pneumatic valve-action, and Figs. 2 and 3 are respectively a vertical transverse section on 25 line 2, 2, and a vertical longitudinal section on line 3, 3, Fig. 1.

Similar letters of reference indicate corresponding parts.

Referring to the drawings, *a* represents 30 the supporting base-plate, *b* an intermediate block, and *c* the top-plate of my improved pneumatic valve-action. To the underside of the base-plate *a* is attached a bellows *d* of the usual construction, the stationary member of 35 which is provided with a regulating screw *d*¹ having a cushion *d*² at its inner end for arresting the movable member of the bellows *d*. The movable member of each bellows *d* is provided with a projecting heel *d*³ which en- 40 gages a bracket *e* that is glued or otherwise attached to the abstract *e*¹ of the piano-action.

All the valve-actions are arranged in two or more tiers in the casing of the upright piano at some distance above the keyboard 45, in the space between the upper front-panel of the piano and the abstracts of the piano-actions. The intermediate block *b* is seated on the base-plate and connected therewith in an air-tight manner by an intermediate layer of 50 soft leather, felt or other material. Each bellows *d* is connected by an angular channel *f* with a valve-chamber *g* arranged in the block *b*, in which chamber a disk-shaped valve *g*¹ is located. The valve-chamber *g* is connected with the atmosphere by an opening 55 *o* in the top-plate, which opening is pro-

vided with a perforated cross-piece *g*³ for guiding the stem *g*² of the valve *g*¹, while the lower part of the stem passes through an opening *o*¹ in the bottom of the valve-chamber *g* into proximity to a diaphragm *h* which extends over a depression *w*¹ of the suction-chest *w*. The suction-chest *w* is connected by a pipe *w*² with the power-bellows by which the suction-action of the suction-chest is sus- 60 65 tained.

The upper and lower faces of the valve *g*¹ are covered with felt or other cushioning material so as to form an air-tight closure with the opening *o* in the top-plate and opening *o*¹ in the bottom of the valve-chamber and forming the connection between the valve-chamber and suction-chest. The opening *o*¹ is provided with a metallic thimble *r* and rim *r*¹ on which latter the valve *g*¹ is seated when in a position of rest. The lower part of the valve-stem *g*² is provided with a cylindrical weight *g*⁴ for producing the quick return of the valve onto its rim or seat *r*¹ when the diaphragm returns to its normal 70 75 position of rest. The space below the diaphragm *h* is connected by a short duct *i* with a pipe *i*¹ which passes through the base-plate *a* to the outside, being then curved upwardly and connected by a flexible tube *i*² 80 85 with the corresponding channel of the tracker, (not shown).

The diaphragm is provided with a small hole *o*² near the circumference of the diaphragm *h*, said hole *o*² facilitating the return 90 of the diaphragm into the depression *w*¹ after it has been called into action by the pressure of the air sucked in through the tracker-channel and connecting-tube, the air in the depression below said opening being drawn 95 into the suction-chest and permitting the return of the diaphragm and valve into the lower normal position of rest.

The operation of my improved pneumatic valve-action is as follows: As soon as a perforation in the note-sheet passes over the inlet-opening of the tracker-channel corresponding to one of the pneumatic valve-actions, air-pressure is established in the space below the diaphragm, so that the suction of the 100 power-bellows exerted in the suction-chest produces the quick lifting of the diaphragm, and valve, so that the latter opens the opening in the bottom of the valve-chamber and closes the opening in the top-plate of the 105 same. The lifting of the valve opens the channel *f*, leading to the bellows *d* and pro-

duces the instant collapsing of the bellows under the suction exerted by the suction chest and thereby the lifting of the abstract by the heel and bracket, the operation of the piano-action and the sounding of the corresponding string. As soon as the opening in the music-sheet has passed the inlet-opening of the tracker-channel, the air is cut off, and the diaphragm quickly returned to its position of rest. For permitting the quick return of the diaphragm and the valve to their normal position, the opening σ^2 in the diaphragm h is called into action by the suction of the power-bellows acting on the suction-chest and the escape of the air from the space below the diaphragm, and thereby the return of the diaphragm and of the valve into their normal position of rest. By the return of the valve into its lower position, the opening in the bottom of the valve-chamber is closed and thereby the connection between the suction-chest and bellows shut off so that the latter is expanded. The movable member of the bellows, the abstract and the piano-action are thereby returned to their normal position. The return-motion of the diaphragm is accomplished in a steady and reliable manner without fluttering, and the valve returned to its normal position by the weight applied to the lower end of its valve-stem, so that the valve is ready for its next

actuation. The valve-action functions in a reliable and effective manner and permits by the detaching of the top-plate and intermediate block from the base-plate the easy 35 cleaning of the valve-action and repairing of the parts, if necessary.

Having thus described my invention, I claim as new and desire to secure by Letters Patent:

40

In a pneumatic valve-action, the combination of a base-plate provided with a depression, a diaphragm extending over said depression, an intermediate block above the base-plate cut away to form a suction-chest 45 located over said diaphragm and having a valve-chamber in its upper part communicating with said suction-chest by means of an opening forming a valve-seat, a valve in said valve-chamber coacting with said valve-seat, and a top-plate placed over said intermediate block and closing said valve-chamber with the exception of an opening above the valve.

In testimony, that I claim the foregoing as 55 my invention, I have signed my name in presence of two subscribing witnesses.

HARRY BAINTON.
